DESIGN FOR A HIGHWAY VEHICLE

Eric Ramstrum, Philadelphia, Pa., assignor to American Car and Foundry Motors Company,
New York, N. Y., a corporation of Delaware

Application June 29, 1938, Serial No. 78,133

Term of patent 14 years

To all whom it may concern:

Be it known that I, Eric Ramstrum, a subject of the King of Sweden, residing at Philadelphia, Philadelphia County, State of Pennsylvania, have invented a new, original, and ornamental Design for a Highway Vehicle, of which the following is a specification, reference being had to the accompanying drawing, which forms a part thereof.

Fig. 2 is a front end elevation of the highway vehicle, and

Fig. 3 is a rear end elevation of the highway vehicle.

The side of the vehicle opposite that shown in Fig. 1 is identical with Fig. 1 with the exception that no door is provided therein.

I claim:

The ornamental design for a highway vehicle, as shown and described.

ERIC RAMSTRUM.
